UNITED STATES PATENT OFFICE.

MARTIN M. JOHNSON, OF GREENVILLE, OHIO.

GAME-TABLE.

No. 811,148.

Specification of Letters Patent.

Patented Jan. 30, 1906.

Application filed February 7, 1905. Serial No. 244,615.

To all whom it may concern:

Be it known that I, MARTIN M. JOHNSON, a citizen of the United States, residing at Greenville, in the county of Darke and State 5 of Ohio, have invented certain new and useful Improvements in Game-Tables, of which the following is a specification.

My invention relates to game-tables, and especially to that class of game-tables where- 10 on a game is played with balls impelled by cues or like devices.

The object of my invention is to provide a game-table for the playing of a game requiring a great degree of skill and precision.

With this and other objects in view the present invention consists in the combination and arrangement of parts, as will be hereinafter more fully described, shown in the accompanying drawings, and particu- 15 larly pointed out in the appended claims, it being understood that changes in the form, proportion, size, and minor details may be made within the scope of the claims without departing from the spirit or sacrificing any of 20 the advantages of the invention.

In the drawings, Figure 1 is a top plan view of my improved game-table. Fig. 2 is a vertical sectional view of my improved game-table, taken on line 2 2 of Fig. 1. Fig. 3 is a 30 detail vertical sectional view of the side cushions of my improved game-table.

Like characters of reference designate cor- 35 responding parts throughout the several views.

In its essential features my invention com- 40 prises a table having a plane surface, preferably square in form and having suitable cushions arranged along each of its sides, as indicated at 1. The cushions 1 are made sec- tional, and between the several sections are provided pocket-openings 3. In its pre- 45 ferred proportion my game-table is provided upon each of its sides with six pocket-open- 50 ings, though it is obvious that any other num- ber may be as well used, and in each of said pocket-openings is provided an aperture 4 through the table-surface, beneath each of which is suspended a bag-like pocket 5, preferably of fabric. The several sections form- 55 ing the cushion along the sides of the tables are covered with fabrics of different colors, so that the cushion along each side of the table differs in color to the other cushions, as indicated by the shading in Fig. 1.

Upon the surface of the table are arranged

a plurality of triangular-shaped resilient buffers upstanding from the table-surface and of a height approximately equaling the height of the side cushions. The triangular buffers are indicated at 6 and are each covered with 60 fabric and preferably differently colored, so that the buffers abutting any one side of the table are colored similar thereto, the color being arranged in the form of a triangle with its base, the side of the table, and its apex ap- 65 proximately at the center thereof. The buffers are so disposed upon the surface of the table as to form ball passage-ways extending entirely across the table from each pocket- 70 opening to the pocket-opening directly oppo- 75 site, as indicated at 7 in Fig. 1, and extending always parallel with the sides of the table. The arrangement of the buffers form obliquely-disposed ball passage-ways 8, as shown in Fig. 1, extending from each corner 75 of the table to the opposite corner and other obliquely-disposed ball passage-ways 9, ex- 80 tending parallel therewith, with each end termin- 85 at a pocket-opening. The table is provided with any approved frame 10 to hold 80 the cushions and set upon any convenient support, as the legs 11. A plurality of balls is provided equal in number to the number of pockets and are colored to correspond with the colors of the cushions. For playing the 85 balls are designed to be arranged as indicated in Fig. 1. The ball A is designed to be pock- 90 eted in pocket A', B in B', C in C', D in D', E in E', and F in F', the ball F being the cue- ball and the last ball to be pocketed.

The foregoing description of the table and apparatus is sufficiently explanatory of the operation and use of the table, and I do not deem a further explanation necessary.

While I have briefly described the pre- 95 ferred game to be played upon my improved table, it is obvious that its use is not limited to the playing of such game only.

While I have shown and described the buffers as being triangular in form and resili- 100 ent, it is obvious that they may be differ- 105 ently formed and rigid and that other changes in the form, proportion, and use of my improved table may be made without departing from the spirit of the invention or the scope of the claims.

Having thus described my invention, what I claim as novel, and desire to secure by Letters Patent, is—

1. A game-table provided with suitable 110

cushions arranged along each of its sides, pocket-openings therethrough, pockets disposed within the pocket-openings and partitions forming passage-ways registering with 5 the pocket - openings and properly proportioned for the passage therethrough of balls.

2. In a game-table upon which balls are to be impelled, suitable cushions arranged and differently colored along each of its sides and 10 provided with a plurality of pocket-openings therethrough, a pocket disposed within each of said pocket-openings and buffers arranged upon the table to form passage-ways, said passage-ways being arranged to register with 15 the pocket-openings and proportioned to permit the passage of a ball.

3. In a game-table upon which balls are to be impelled, suitable cushions arranged and differently colored along each of its sides and 20 provided with a plurality of pocket-openings therethrough, a pocket disposed within each of said pocket-openings and resilient buffers geometrically arranged upon the surface of said table to form passage-ways and so dis-

posed that the passage-ways register with the 25 pocket-openings.

4. A game-table apparatus comprising a table, suitable cushions arranged and differently colored along each of its sides and provided with a plurality of pocket - openings 30 therethrough, a ball - receiving pocket disposed within each of said pocket-openings, a plurality of triangular - shaped buffers arranged upon the surface of the table and to form a plurality of ball passage-ways parallel 35 with each of the table sides and others extending obliquely thereto and a plurality of series of balls, each series colored to correspond with the color of one of the side cushions and equal in number to the pocket-open- 40 ings in each cushion.

In testimony whereof I affix my signature in presence of two witnesses.

MARTIN M. JOHNSON.
